UNITED STATES PATENT OFFICE.

RALPH G. WRIGHT AND KIRK K. WRIGHT, OF BUFFALO, NEW YORK.

APPARATUS FOR WASHING BOTTLES.

No. 850,199.

Specification of Letters Patent.

Patented April 16, 1907.

Application filed July 28, 1903. Serial No. 167,261.

To all whom it may concern:

Be it known that we, RALPH G. WRIGHT and KIRK K. WRIGHT, residing at Buffalo, in the county of Erie and State of New York, have invented certain new and useful Improvements in Apparatus for Washing Bottles, of which the following is a full, clear, and exact description, such as will enable others skilled in the art to which it appertains to make and use the same.

Our invention relates to improvements in apparatus for washing bottles or other like receptacles.

The object of our invention is to provide an apparatus in which a bottle may be thoroughly washed and rinsed and dried and sterilized.

Other objects will appear from the herein-after description.

20 In carrying out our object we produce an apparatus that is cheap and simple in construction, that operates effectively, and performs the work rapidly.

25 The nature of the invention will more fully appear from the following description, taken in connection with the accompanying drawings, which form a part of this specification.

Referring to the drawings, in which the same reference characters represent the same parts in the different views, Figure 1 is a perspective view of our apparatus. Fig. 2 is a longitudinal vertical section thereof through the middle of the apparatus, taken on the line 2-2 of Fig. 3. Fig. 3 is a plan view of the apparatus with the hood shown in Fig. 1 removed. Fig. 4 is a plan view of our improved frame for holding the bottles in the crate while the crate is passing through the apparatus with the bottles to be washed. 40 Fig. 5 is a section of Fig. 4 on the line 5-5. Fig. 6 is a perspective view of the frame.

In all the drawings the part marked 1 represents the framework which supports the washing-tank 2. This tank is divided by a 45 partition 3 into two compartments A and B.

4 is a shelf on which are supported rotary pumps 5 and 6, which are driven by means of a belt 7, passing over one of the two pulleys 8 and 8^a, one of these pulleys being an idler. 50 9 is an inlet-pipe leading from the compartment A of the tank to the pump 5, and 10 is another inlet-pipe leading from the compartment B to the pump 6.

11 is a discharge-pipe extending from the pump 5 into or over the compartment A. 55 Connected to this pipe is a series of branch

pipes 12, there being shown in this apparatus three of such pipes, and each of the pipes is provided with four openings 12^a in the upper side thereof through which water is forced into the bottles to be washed, these openings being so arranged or spaced that they will come directly under the mouth of the bottle when the crate carrying the bottles is properly placed in the machine. Leading from the pump 6 into the compartment B are similar pipes 13 and 14, said pipes being also provided with openings 14^a.

15 is another pipe leading into this compartment having branch pipes 16 connected thereto, with openings 16^a, similar to the pipes heretofore described. This pipe 15 is adapted to be connected to a source of live-steam supply.

17 is a partition-plate in the compartment A. Located over this partition-plate and directly under the pipes 12 is a plate or trough 18. Onto this plate 18 falls the water which comes out of the bottles while being washed. This plate is inclined, as shown in 80 the drawings, to throw the water away from the partition 17. This arrangement is such that the dirt, &c., coming out of the bottles with the water will fall into that part of the compartment A to the right of the partition 85 17 and settle in said part, so that the water flowing over the top of the partition to that part of the compartment to the left will not carry any sediment with it, and therefore the sediment will be prevented from being drawn 90 into the pump 5 through the inlet-pipe 9.

19, 20, and 21 are overflow-pipes removably connected to the bottom of the tank, so that they can be taken out to permit the water to run out of the bottom of the tank, so 95 that the tank can be emptied and cleaned. Extending along the top of the tank and beyond each end thereof are two pieces of angle-iron 22 23, forming a track on which the cases containing the bottles to be washed are 100 moved. This track is properly supported and secured to the tank, and the bottom flange of each angle-iron is provided with a series of rollers 24, on which the edges of the bottle-containing cases rest, so that the said 105 cases may be more easily moved along the track.

25 is a hood fitted over the tank to deflect the water and steam forced through the openings 12^a, 14^a, and 16^a down into the compartments A and B when the bottles are not covering said openings.

In this apparatus the bottles may be washed without removing them from the wagon delivery crates or cases. As shown in this particular apparatus, each of the cases is 5 adapted to hold twelve bottles and in the operation of washing these cases are turned upside down and moved along the track, so that the mouth of each bottle will come over each one of the openings 12^a, 14^a, or 16^a. To hold 10 the bottles in the case when the case is inverted, we have provided a specially-constructed frame. (Shown in Figs. 2, 4, and 5.) This frame consists of two side pieces 26 and end pieces 27. The space between the 15 two sides 26 is divided into three equal parts for the three rows of bottles held in the crates by the plates 28, which extend longitudinally, the ends being upturned, as shown at 28^a, and secured to the end pieces 27. 20 29 are cross-pieces secured to the pieces 28. The ends of these cross-pieces are upturned, as shown at 29^a, and have secured to the ends thereof the longitudinal rods 30. This frame is placed over the crate, with the ends and 25 sides resting against the upper edge of the ends and sides of the crate, the rods 30 pressing against the outsides of the two outside rows of bottles in the crate to keep these rows from moving toward the sides of the 30 crate when the crate is inverted. The plates 28 and 29 extending between the inner bottles of the crate hold them in position. When the crate is inverted, the edges of the side pieces 26 rest upon the rollers, and the frame 35 securely holds the bottles in position in the crate.

The apparatus operates as follows: Each of the compartments A and B is filled, or partially filled, with water, either hot or cold. 40 The first crate of bottles is placed upon the track and pushed along until the bottles come directly over the openings 12^a in the series of branch pipes 12, there being a mark or gage 22^a and 23^a on the track to indicate to the operator when the crate is over these openings. The pumps are started and water is drawn from the compartment A through the inlet-pipe 9 into the pump 5 and is forced through the pipe 11, branch pipes 12, and 45 openings 12^a into the bottles, thoroughly cleansing them. The water from the bottles falls upon the plate 18 back into the compartment. The dirt and sediment is kept away from the inlet-pipe 9 by the plate 17, the sediment settling in that part of the compartment to the right of this plate. When 50 the first set of bottles is washed, another crate is placed on the track and pushed along over the openings 12^a and the first crate is moved to the position *a*, where the bottles drain. When the second crate of bottles is 55 washed, another is placed on the track and moved along to the first position *b*, the crate being shoved to the position directly over the 60 openings 14^a, where the pump 6 forces the

water through these openings into the bottles to rinse them, the water being drawn out of the compartment B and circulated through the inlet-pipe 10, pump 6, outlet-pipe 13, and branch pipes 14. When the third crate of 70 bottles is washed, the fourth is put on the track and the prior crates moved along one step, the first crate being shoved over the opening 16^a to the position *c*, where steam is forced into the bottles to dry and thoroughly 75 sterilize them. As the bottles are washed and sterilized the crates are moved along the track to the right, where they pass out from under the hood 25, when they are then removed and are ready to be filled. 80

While we have shown the inlet-pipes 9 and 10 of the pumps connected to the tank, so that the water contained in the tank may be circulated through the tank, we may, if desired, connect these inlet-pipes to an independent supply, so that the water may not be used over again, but fresh water will be continually supplied to the tank. When this is done, the excess of water will pass through the overflow-pipes 19, 20, and 21 or through 85 some other suitable connection. The openings 12^a, 14^a, and 16^a may also be provided with small upwardly-projecting pipes or nipples. 90

While we have shown and described a certain apparatus for carrying out the object of our invention, it is to be distinctly understood, however, that we do not intend to confine ourselves to the exact construction, as various changes or modifications may be 95 made within the scope of our invention without departing from the spirit thereof.

Having now fully described our invention, what we claim as new, and desire to secure by Letters Patent, is— 100

1. In an apparatus for washing and sterilizing bottles, a tank divided into compartments, means for supporting the bottles over the tank, a series of branch pipes in one compartment, means for forcing water through 105 said pipes to wash the bottles, a series of pipes in another compartment, means for supplying water to these pipes to rinse the bottles, and means for supplying a drying and sterilizing medium to the bottles after 110 they have been rinsed.

2. In an apparatus for washing and sterilizing bottles, a tank divided into compartments, a series of branch pipes in one compartment, means for forcing water through 115 said pipes to wash the bottles, a series of pipes in the other compartment, means for supplying water to these pipes to rinse the bottles, and another series of pipes in this second compartment through which steam may be 120 forced to dry and sterilize the bottles after 125 being rinsed.

3. In a bottle washing and sterilizing apparatus, a tank divided into two compartments, a track adapted to support bottles to, 130

be washed extending across the tank, a water-supply pipe extending into the first compartment, branches connected to this pipe having openings therein through which water 5 may be forced, means for forcing the water through the openings for the purpose of washing the bottles, a pipe extending into the second compartment, branches connected to this pipe having openings therein 10 through which water may be forced into the bottles, means for forcing the water into the pipes through the openings to rinse the bottles, another pipe extending into the second compartment, branches connected thereto 15 having openings therein, said last-mentioned pipes adapted to have steam forced therein to dry and sterilize the bottles.

4. In a bottle-washing apparatus, a tank divided into compartments, a track extending 20 longitudinally over the tank, a series of pipes having openings therein located in one compartment, means for forcing water through said pipes to wash the bottles, a trough located under said pipes, a partition 25 in said compartment, a series of pipes in the second compartment having openings therein through which water is forced to rinse the bottles, means for forcing water through said 30 openings, and another series of pipes having openings therein through which steam may be forced to dry and sterilize the bottles.

5. In an apparatus for washing bottles, a tank divided into compartments, pumps, an inlet-pipe leading from one pump to one compartment, branch pipes connected to said 35 pipe having openings therein through which water may be forced to wash bottles, a trough or plate in the tank under said branch pipes, a partition undersaid trough, a return-pipe leading from said compartment to the 40

pump, a pipe leading from another pump to another compartment, an outlet-pipe leading from this compartment to the pump, branch pipes connected to said first-mentioned pipe and having openings therein through which 45 a rinsing medium may be supplied to the bottles, another pipe leading to the second compartment, a series of branches connected to this latter pipe, there being openings therein through which steam may be forced 50 to dry and sterilize bottles after being rinsed, supporting means over the tank and adapted to support crates containing bottles to be washed and a hood over the tank and supporting means, as and for the purpose set 55 forth.

6. In an apparatus for washing bottles, a frame, longitudinal strips connected to said frame at two ends thereof, cross-pieces connected to said strips, said frame adapted to 60 be placed over crate containing bottles to engage the sides of the crate whereby the frame is held in place in the crate and the bottles are prevented from falling out of the crate when the crate is inverted.

7. In an apparatus for washing bottles, a frame, strips dividing the frame, said strips being connected to ends of the frames, cross-pieces connected to said strips and rods connected to the ends of the cross-pieces, said 70 frame adapted to be placed over crate containing bottles to hold the bottles in place in the crate when crate is inverted.

In testimony whereof we affix our signatures in the presence of two witnesses.
